SPACE DISCHARGE DEVICE AND METHOD
OF MAKING IT

Victor O. Allen, Madison, N. J., assignor, by mesne assignments, to Radio Corporation of America, a corporation of Delaware

No Drawing. Application April 4, 1930,
Serial No. 441,703

14 Claims. (Cl. 250—27.5)

This invention relates to methods and means of manufacturing space discharge devices and with particularity to a novel method of manufacturing devices employing electron emissive members.

As is well known in the manufacture of such devices as audions, rectifiers, etc., it is the usual practice to employ so-called getters, and clean-up agents to expedite the evacuation of the device.

10 It has also been proposed to employ chemical agents which are left permanently within the device to act as "keepers" so far as occluded and residual gases within the device are concerned. No thoroughly satisfactory single chemical agent 15 may be employed as both getter and "keeper" with different types of electron emitters.

Applicant is aware that it has been proposed heretofore to employ as a getter, magnesium. However the utility of magnesium is limited in 20 its advantages to devices employing emitters of the thoriated tungsten type. In order that the magnesium may be rendered effective it is necessary to subject it to a flashing operation whereby it becomes vaporized. Substantially the entire clean-up action of the magnesium is therefore effective only while it is in a vaporized condition. Aside from this limitation there is another disadvantage which of course is common to all vaporizable getters, namely that it is difficult 25 to confine the vaporized material to one particular portion of the device, and when the vaporized material cools it undesirably deposits in the form of a non-transparent mirror on the walls and other parts of the device. It has been 30 proved by many tests that after the manufacture of a device and while it is in use the effectiveness of the magnesium is almost entirely negligible. Devices have been actually made without employing the magnesium getter and said devices have 35 been found to possess as good a life and operating characteristics including freedom from gases as with devices employing magnesium.

Accordingly it is another important object of 40 the present invention to provide a chemical agent or agents for electron discharge devices and possessing all the advantages of the usual magnesium getter and without the above noted and other disadvantages incident to the use of magnesium.

45 Another object of the invention is to provide a novel chemical clean-up agent for expediting the evacuation of electron discharge devices which agent also acts as an effective "keeper" during the entire life of the device.

50 Another object is to provide a non-vaporizable

chemical agent which acts as an effective getter and "keeper" while in the non-vaporized state.

Another object of the invention is to provide a novel type of clean-up agent having a greater capacity to absorb or adsorb residual gases both during the manufacture and during the life of the device.

Another object of the invention is to employ as a getter or clean-up agent the same material which can be used for electron emissive purposes.

5 A feature of the invention relates to the use of a compound of the alkali earth group and the alkali metal group containing oxygen, as a getter and "keeper".

Another feature of the invention relates to the method of producing a getter and "keeper" within an electron discharge device.

Another feature of the invention relates to the method of treating a carbonate of the alkali earth group to produce a chemical agent which acts both as getter and "keeper".

10 A further feature of the invention relates to the method of producing a non-vaporized chemical agent capable of acting as a getter and "keeper".

15 A further feature relates to the method of subjecting a chemical agent within an electron discharge device to successive treatments whereby said agent is first decomposed to produce an 30 oxide which acts as a clean-up agent, and also liberates the gas or gases acting to flush out any air or other gas within the device.

20 A further feature of the invention relates to the method of treating an oxalate or carbonate 35 of the alkali or alkali earth groups to produce an oxide by decomposition without liberating any oxidizing gases or vapors.

25 Other features and advantages of the invention not specifically enumerated will be apparent 40 after a consideration of the following detail descriptions and the appended claims.

30 It is a well known fact that the oxides of the alkali earth group have a great affinity for combining with carbon dioxide, carbon monoxide, 45 water vapor and many other gases which as is well known interfere with the proper evacuation and operation of electron discharge devices. This characteristic is so marked that these oxides cannot be exposed under ordinary conditions 50 to the atmosphere without being immediately attacked.

35 It is also known that the addition of carbon to barium or strontium carbonates considerably lowers the temperature required for decomposi- 55

tion of such carbonates, and that during this reaction carbon monoxide is liberated instead of carbon dioxide, as is shown by the following equation—

In the manufacture of such devices as audions or the like it is recognized that carbon monoxide gas being a strong reducing agent is an ideal gas 10 for flushing out the device before the final clean up agent. In accordance with the present invention therefore it is proposed to employ any suitable salt either of the alkali metal or the alkali earth groups. For example oxalates or 15 carbonates of barium and/or strontium are particularly advantageous in achieving the objects of the invention. These salts are mixed with an organic material or any material containing organic carbon either in the free or associated 20 states and subjected to heat. Thus in manufacturing audions, lamps, or vacuum tubes generally the following procedure has actually been employed and found to produce very good results. A mixture of barium and strontium carbonates with organic carbon is mounted at any 25 convenient point within the envelope of the device. Preferably this mixture is mounted in the device at such a point that its temperature is not sufficiently raised to render it electronically 30 active. Thus the mixture may be compressed within a small cup or container and this container mounted at a distance from the heater element or filament of the device.

The device with the chemical thus mounted 35 therein is placed on the pump and subjected to the usual preliminary heating and evacuation. As a result of these initial steps the carbonates are completely decomposed and reduced to their 40 oxides in accordance with the equation given above. At the same time carbon monoxide is liberated and acts to flush out any air or other residual gases within the device, and simultaneously reduces oxides which may be on or occluded within the walls or metallic elements 45 within the device. After the evacuation and decomposition of the carbonates have been completed the elements and the chemical agent are simultaneously raised to a relatively high temperature, preferably by induced radio frequency 50 currents in the usual manner, and during this heat treatment the evacuation is continued and completed in the regular manner. When the 55 evacuation has been proceeded with to the required extent the device is sealed off the pump. Consequently there is retained within the device a comparatively large quantity of barium and strontium oxide which function as "keepers" during the actual life of the device to react with 60 gases liberated from the elements and surfaces within the device.

From the foregoing it will be seen that there is produced a chemical agent which acts during the initial stages of evacuation to expedite the 65 evacuating time and also remains within the device to act as "keeper" and since the "keeping" action of the agent is substantially entirely independent of its vaporization it is effective at all times during the life of the device regardless of the operating temperature thereof.

70 Inasmuch as the barium and strontium oxides resulting from the decomposing process hereinabove described are themselves electronically emissive and are the same materials that are ordinarily employed for electron emissive cathodes, it is necessary to mount the chemical agents

above described at such a point within the device that they do not become hot, to render them electronically active during the life of the tube.

What is claimed is:

1. The method of evacuating the enclosing 5 envelope of an electron discharge device having an electron emitting cathode which comprises heating apart from the cathode a stable salt of the alkali earth group in the presence of a reducing agent to produce an alkali earth oxide, 10 subjecting the envelope to a pumping operation during said heating, and resubjecting the oxide to heat to effect a final evacuation.

2. The method of evacuating an electron discharge device having an electron emissive cathode, which includes the step of heating apart from said cathode, a carbonate of an alkali earth metal in the presence of a reducing agent within 15 the device.

3. The method of evacuating an electron discharge device having an electron emissive cathode which includes the step of heating apart from said cathode, a carbonate of an alkali earth metal in the presence of organic carbon within 20 the device.

4. The method of evacuating an electron discharge device having an electron emissive cathode which includes the step of heating apart from said cathode, a mixture of barium carbonate in the presence of a reducing agent within the device. 25

5. The method of evacuating an electron discharge device having an electron emissive cathode which includes the step of heating apart from said cathode, a mixture of barium carbonate in the presence of organic carbon within the device 30 to reduce the barium carbonate to barium oxide and then heating the barium oxide to complete the evacuation.

6. The method of evacuating an electron discharge device having an electron emissive cathode which comprises mounting a mixture of barium and strontium carbonates together with organic carbon at a suitable location within the device where it will not be materially affected by cathode heat, reducing said carbonates to their 40 oxides, subjecting the oxides to heat and simultaneously subjecting the device to exhaustion.

7. The method of completing the evacuation of a partially evacuated electron discharge device 50 which comprises heating a stable salt of the alkali earth group to liberate a quantity of carbon monoxide within the device and to reduce said salt to the oxide, removing said carbon monoxide, and then heating said oxide to effect a final clean-up.

8. The method of completing the evacuation of a partially evacuated electron discharge device which includes heating a carbonate of the alkali earth group to evolve a quantity of carbon monoxide within the device and to reduce said salt to the oxide, removing said carbon monoxide, 60 and then heating said oxide to effect a final clean-up.

9. An electron discharge device having on the interior thereof an electron emissive cathode and a separate quantity of a carbonate of the alkali earth group situated within the device at a point where it will not be materially affected by the 65 cathode heat.

10. An electron discharge device having on the interior thereof an electron emissive member and a separate quantity of material apart from said member comprising a mixture of barium and strontium carbonates and organic carbon. 70

11. The method of evacuating an electron discharge device having an electron emitting cathode 75

which comprises mounting a mixture of an oxalate of the alkali earth group and organic carbon within the device and subjecting said mixture to heat apart from said cathode.

5. 12. The method of evacuating an electron discharge device having an electron emitting cathode which comprises mounting a mixture of an oxalate of an alkali metal and organic carbon within the device and subjecting said mixture to heat apart from said cathode.

10. 13. The method of manufacturing an electron discharge device having an evacuated envelope which comprises subjecting a mixture of a salt of the alkali earth group and a reducing agent

placed within the envelope to heat to effect a reaction therebetween to form an oxide of the metal of the salt and carbon monoxide and evacuating the envelope during the reaction.

14. The method of evacuating an electron discharge device having an electron emitting cathode therein which includes the step of heating a mixture of barium and strontium carbonates in the presence of organic carbon within the device and apart from said cathode to effect a reaction therebetween to provide barium and strontium oxides within said device.

VICTOR O. ALLEN.
